UNITED STATES PATENT OFFICE.

DAVID G. WEEMS, OF BALTIMORE, MARYLAND, ASSIGNOR TO THE ELECTRO-AUTOMATIC TRANSIT COMPANY, OF SAME PLACE.

RAILWAY.

SPECIFICATION forming part of Letters Patent No. 406,802, dated July 9, 1889.

Application filed December 28, 1888. Serial No. 294,889. (No model.)

To all whom it may concern:

Be it known that I, DAVID G. WEEMS, a citizen of the United States, residing at the city of Baltimore and State of Maryland, have 5 invented certain new and useful Improvements in Railways, of which the following is a full and clear description, reference being had to the accompanying drawing, forming part of this specification, in which the figure 10 represents a view taken transversely through the rails and stringers, and showing an end view of a car or carrier adapted to travel thereon.

My invention relates to certain improvements in railways, and especially in the rails thereof; and the same consists, essentially, in providing or forming the rail with an upper tread or bearing-surface and a laterally-extending flange having a tread or surface upon 20 which independent wheels or series of wheels travel.

To enable others skilled in the art to which my invention appertains to make and use the same, I will now describe its construction and 25 indicate the manner in which the same is carried out.

In the said drawing, A represents a suitable road bed or frame, having the longitudinal stringers or beams B, upon which the rails 30 are laid. These rails C are angular in cross-section, and are each formed or provided with an upper tread or bearing-surface a and a lower laterally-projecting arm or bearing-surface b. The rails are spiked or bolted to the 35 upper inner corners of the stringers or longitudinal beams, their inner angular corners adapting them to be closely fitted to the inner corners of the stringers or beams, as shown, and, if desired, the under surface of 40 that portion of the rail which lies upon the top of the stringer may be formed with a longitudinal rib b', which is driven or fitted into a groove in the top surface of said stringer or beam, whereby said rail is more securely held 45 and the danger of the rails spreading reduced to a minimum.

It is understood that the rails thus described are adapted for any well-known form of vehicle or carrier; but as the danger of said vehicle or carrier jumping the track, especially

when rounding curves, is well known, I deem it essential to utilize the under surface of the projecting flange b of said rail as a bearing-surface for other wheels, which, by engaging the under surface of the said arm, prevents 55 the objectionable and often dangerous results above mentioned, as I shall hereinafter describe.

The carrier or vehicle C' which I prefer to use in connection with my improved rail is 60 provided with the usual bearing-wheels D, which are designed to travel upon the upper surface of the horizontal arm a, and within the frame of the carrier is mounted, in any suitable manner, one or more shafts or axles 65 D', upon the outer ends of which are mounted wheels d, as shown; or, if preferred, any other suitable rolling or sliding friction bearing or stop may be employed.

In the figure I illustrate the wheels d as being located slightly below the under surface of the vertical arm of the rails, and these wheels are intended to come into engagement with the lower bearing-surface or track, when the centrifugal force incident to the rapid 70 travel of the vehicle or carrier in rounding curves tends to lift the main bearing-wheel from the track and thereby derail the vehicle. 75

It will be readily seen upon an examination of the drawing that as soon as the main 80 bearing-wheels are lifted from their track or surface the underlying wheels d are likewise lifted into contact with the contiguous bearing surface or track, and thereby overcome the tendency of the carrier leaving the rails or 85 track.

The rails, it will be observed, may be readily rolled, and they may be reversed when one surface is worn to any considerable extent, in which case the vertical arm b becomes the 90 horizontal arm, the inner surface of the rail (in the first instance) being now utilized as the track or bearing-surface for the main wheels, the outer side of the rail serving as the bearing for the lower or supplemental 95 wheels.

Having thus described my invention, what I claim as new, and desire to secure by Letters Patent, is—

1. The combination, with a car having bear- 100

ing-wheels, a shaft below the main axles, and supplemental wheels thereon, of an angular rail having an upper tread or bearing-surface for the main wheels, and a laterally-projecting arm or flange, the under surface of which forms a track for the supplemental wheels when brought into contact therewith, substantially as described.

2. The combination, with a carrier or vehicle having the wheels D and d, of angular rails between said wheels, and each consisting of a horizontal arm having a bearing-surface or track for the wheels D, and a vertical

arm c, having a laterally-projecting flange b, the lower under surface of which serves as a track or surface for the other wheels d, the said wheels d being normally slightly below the vertical arm of the rail and being brought into contact with its lower bearing-surface when the main wheels D attempt to leave their track or surface, substantially as herein described.

DAVID G. WEEMS.
